[57] ABSTRACT

Material handling apparatus is disclosed for receiving, transporting and dumping a material.

The material handling apparatus has a dump type box having a bottom portion, opposed side portions and a back portion defining a load carrying cavity. The dump type box also has a front fork engaging member on one portion of a side portion and said bottom portion, a rear fork engaging member on the one portion and spaced from the front fork engaging member, and a fork engaging stirrup member on the one portion, disposed between the front fork engaging member and the rear fork engaging member and pivotable on the one portion. A lifting fork device is reciprocable in a vertical plane with respect to the supporting surface and has a tine.

The tine is insertable through the fork engaging stirrup member while the dump type box is in the rest position and into registry with the front fork engaging member and the rear fork engaging member so that the tine engages the front fork engaging member and the rear fork engaging member when the tine moves the dump type box away from the rest position into a box transporting position to permit filling of the load carrying cavity with a material. The tine then is operable to return the filled dump type box to the rest position to permit the tine to clear the front fork engaging member, while the filled dump type box is in the rest position. The tine then is operable to move the filled dump type box away from the rest position so that the filled dump type box rotates about the fork engaging stirrup member into a dumping position thereby emptying the filled load carrying cavity.

MATERIAL HANDLING APPARATUS

Conventional devices are of the type disclosed in the following patents:

U.S. Patent No.	Inventor	Issued
2,304,649	McDaniels	12/8/42
2,689,054	Martin	9/14/54
3,013,684	King et al.	12/19/61
3,199,697	Gatz et al.	8/10/65
3,226,783	Draxler	1/4/66
3,486,648	Dewald	12/30/69

The Dewald patent discloses a dumping bin for use with a fork lift tractor. The dumping bin is self contained but requires the operator to pull a latch thereby causing dumping of the bin.

The King et al. patent shows a dumping box and an additional attachment on the fork lift truck which is operable to dump the box.

In the Martin Patent, the dump box is pivotable and has a fork lift attachment for causing the dumping of the box.

The Gatz et al. patent uses a complicated mechanism usable with the fork lift to tilt the fork at an angle for use in dumping.

The Draxler patent uses an overhead boom type arrangement for use in a fork lift truck to cause dumping of the box.

In the McDaniels patent, the box is dumped by a complicated chain type overhead boom.

OBJECTS OF THE INVENTION

It is the general object of this invention to avoid and overcome the foregoing and other difficulties of and objections to prior art practices by the provision of improved material handling apparatus for receiving, transporting and dumping material. The improved apparatus:

1. eliminates the use of the conventional latch to dump the material;
2. eliminates the use of the conventional attachment on the associated fork lift which attachment is operable to dump the box;
3. does not require a complicated mechanism on the fork lift to cause dumping;
4. eliminates the use of overhead booms to cause dumping of the box;
5. is simple and rugged in structure;
6. has few moving parts;
7. requires little or no maintenance;
8. has a long operational life; and
9. is readily adapted to any required volume of load carrying cavity.

BRIEF SUMMARY OF THE INVENTION

The aforesaid objects of this invention, and other objects which will become apparent as the description proceeds, are achieved by providing an improved bulk material handling apparatus.

The material handling apparatus has a dump type box having a bottom portion, opposed side portions and a back portion defining a load carrying cavity. The dump type box also has a front fork engaging member on one portion of a side portion and said bottom portion, a rear fork engaging member on the one portion and spaced from the front fork engaging member, and a fork engaging stirrup member on the one portion, disposed between the front fork engaging member and the rear fork engaging member and pivotable on the one portion. A lifting fork device is reciprocable in a vertical plane with respect to the supporting surface and has a tine.

The tine is insertable through the fork engaging stirrup member while the dump type box is in the rest position and into registry with the front fork engaging member and the rear fork engaging member so that the tine engages the front fork engaging member and the rear fork engaging member when the tine moves the dump type box away from the rest position into a box transporting position to permit filling of the load

carrying cavity with a material. The tine then is operable to return the filled dump type box to the rest position to permit the tine to clear the front fork engaging member, while the filled dump type box is in the rest position. The tine then is operable to move the filled dump type box away from the rest position so that the filled dump type box rotates about the fork engaging stirrup member into a dumping position thereby emptying the filled load carrying cavity.

10 BRIEF DESCRIPTION OF THE SEVERAL VIEWS OF THE DRAWINGS

For a better understanding of this invention, reference should be had to the accompanying drawings, wherein like numerals of reference indicate similar parts through the several views and wherein:

FIG. 1A is a perspective view taken from the back portion of a dump type box of the present invention and showing the flag holder, the front tine engaging member, the tine engaging stirrup member, the rear tine engaging member, the first stop means on the side portions of the box for limiting the pivotal dumping movement of the box and the second stop means on the back portion of the box for limiting the relative movement of the box with respect to the lifting fork truck;

FIG. 1B is a perspective view of a conventional fork lift truck taken from the back portion of such truck and showing the tines, the mast on which the tines are vertically reciprocable, and the oscillating mechanism, such as a pair of fluid cylinders or the like, for oscillating the mast and the tines about a lower pivot point (not shown) for the mast on the truck frame;

FIG. 2 is a view similar to a side elevational view of the dump type box taken along the lines 2-2 of FIG. 1A in the direction of the arrows and showing an alternative embodiment of the second stop means mounted on the side portions of the dump type box;

FIG. 3 is a back view taken along the lines 3-3 of FIG. 1A in the direction of the arrows of the dump type box shown in FIG. 1A;

FIG. 4 is a side elevational schematic view showing the dump type box and the tines with the box in its normal rest position on a supporting surface, such as the floor or the like, and showing the tines in engagement with the opposed front fork engaging member and the opposed rear fork engaging members preparatory for the lifting operation;

FIG. 5 is a view similar to FIG. 4 and showing the loaded dump type box and tines in the angled transporting position preparatory for movement by the fork lift truck to a dumping area;

FIG. 6 is a view similar to FIGS. 4 and 5 showing the dump box in the dumping position just prior to engagement of the first stop means by the outer ends of the tines;

FIG. 7 is a view similar to FIG. 3 of an alternative embodiment of the dumping type box showing the stirrup member mounted on the bottom portion of the box, having the rear fork engaging member removed for clarity and showing a single broad tine in engagement with the stirrup member;

FIG. 8 is a view similar to FIG. 7 and showing another alternative embodiment having a vertically mounted stirrup member on one side portion of the dump type box and having the rear fork engaging member removed for clarity; and

FIG. 9 is a view similar to FIG. 2 of a further alternative embodiment of the box and showing two types of a first guard means (two guard means of one type being shown in dotted lines for use with the first stop means and the other of which dotted line guard means is employed without the first stop means) and also showing an arcuate type first guard means in solid lines, and showing further a second guard means, one of which is shown in dotted lines and is of straight line type and the other of which is shown in solid lines and being arcuate in shape.

Although the principles of this invention are broadly applicable to dump type boxes in general, this invention is par-

ticularly adapted for use in conjunction with a dump type box for use with various forms of a fork lift truck and hence it has been so illustrated and will be so described.

DETAILED DESCRIPTION

With specific reference to the form of this invention illustrated in the drawings, and referring particularly to FIGS. 1A,2,3,4-6, a dump type box of the present invention is generally indicated by the reference numeral 10.

DUMP BOX 10

This dump type box 10 has a bottom portion 10a (FIGS. 1A,2-6), opposed side portions 10b (FIGS. 1A,2-6) and a back portion 10c (FIGS. 1A,2-6) which together define a load carrying cavity 12 (FIGS. 1A). The bottom portion 10a of the box 10 is normally adapted to rest in a normal rest position on a supporting surface, such as for example, the floor 14 or the like (FIGS. 4-6).

The dump type box 10 also has (on the side portions 10b) opposed front fork engaging members 16 (FIGS. 1A,2,4-6), opposed rear fork engaging members 18 (FIGS. 1A,2-6) and opposed fork engaging stirrup members 20 (FIGS. 1A,2-6). Each stirrup member 20 is disposed between a front member 16 and a rear member 18 and is pivotable at 22 (FIGS. 1A,2-6) on an outboard bearing bracket 24 (FIGS. 1A,2-6). As shown in FIGS. 1, 2-6, the pivot 22 consists of a shaft which is welded to the top portions of each of the stirrup members 20 and is journaled in the side portion 10b and the bottom portions of the outboard bearing bracket 24. As shown in FIGS. 1A,2-6, the dump type box 10 is provided with flag holders 25 in which flags (not shown) may be mounted. Such flag holders 25 can be mounted on the forward and upper portions of the side portions 10b (FIGS. 1A,2-6) or on the back portion 10c (not shown).

TRUCK 26

This truck 26 (FIG. 1B) may be of the type identified by the trade name "Hyster" or Challenger type No. 225, manufactured by the Hyster Company, Danville, Illinois. The truck 26 has a pair of tines 28 (FIGS. 1B,4-6) mounted on a tine bracket 30 (FIG. 1B), which tine bracket 30 is reciprocable on a mast 32 of the truck 26. The means 31 (FIG. 1B) utilized to reciprocate the tines 28 vertically has racks 34 (FIG. 1B) on the mast 32 (FIG. 1B) and engageable with pinions (not shown) on the tine bracket 30 and a drive means, such as a motor (not shown) or the like connected to the pinions (not shown) for moving the tines 28 up and down on the mast 32. The oscillating means 40 (FIG. 1B) for moving the mast 32 and the tines 28 forward arcuately or backward arcuately about a fixed pivot (not shown) of the mast 32 on a frame 44 of the truck 26 is, for example, a pair of fluid cylinders 46 (FIG. 1B) or the like.

OPERATION

While the dump type box is in the normal rest position shown in FIG. 4 (namely having its bottom portion 10a resting on such floor 14), the tines 28 are insertable through a stirrup cavity 20a (FIGS. 1A, 2-3) of the stirrup members 20 and into registry with the front members 16 and the rear members 18. Energization of the reciprocating means 31 (FIG. 1B) on the truck 26 raises the tines 28 into engagement with the front members 16 and the rear members 18, it being noted from a consideration of FIG. 2 that the top portion of the stirrup cavity 20a clears the tines 28 by a distance C (FIG. 2). Thereafter the reciprocating mechanism 31 on the truck 26 raises for example, the box 10 to a position a considerable distance above the ground or floor 14 and the oscillating means or mechanism 40 (FIG. 1B) tilts the mast 32 backwardly through an angle A, (FIG. 5) into the box transporting position to permit, for example, filling of the load carrying cavity 12 with a bulk material 48 (FIG. 6), such as coal, dirt, snow or the like, or to trans-

port a now filled box 10 to a dumping location or area (not shown in FIG. 5).

When, for example, the truck 26 has transported the box 10 filled with the bulk material 48 to a dumping location L_D (FIG. 6), the oscillating mechanism 40 (FIG. 1B) on the truck 26 moves the tines 28 and the now filled box 10 to a position (not shown) substantially parallel to a floor or ground 14 indicated by the dotted line 14 in FIG. 6. Then the reciprocating mechanism 31 on the truck 26 lowers the now horizontally disposed loaded box 10 to the rest position shown in FIG. 4. The truck 26 then further lowers the tines 28 from engagement with the front members 16 and the rear members 18 so that the forward portions of the tines 28 may be withdrawn to the position shown in FIG. 6 and so that the forward portions of the tines 28 backwardly clear the front members 16.

Thereafter the reciprocating mechanism 31 on the truck 26 raises the tines 28 to the position shown in FIG. 6 so that the box 10 pivots in a counterclockwise direction (as shown by the arrow in FIG. 6) on the pivot 22 to permit the bulk material 48 to pour out of the open end of the box 10 onto the ground 14. This rotating dumping movement of the box 10 (shown in FIG. 6) is limited either by the forward portions of the bottom portion 10a striking the floor or ground 14 (which ground 14 is indicated by the dotted horizontal line in FIG. 6) or by engagement of the first stop means 50 shown in FIGS. 1A,2-6 engaging the outboard portions of the tines 28. The first stop means 50 is suitably a pair of rods or the like mounted on the upper forward portions of the side portions 10b of the box 10.

As is shown in FIGS. 1A,3-6, the rear portions or back portion 10c of the box 10 may be provided with a horizontally disposed second stop means 52, suitably a pair of rods or the like, welded to the back portion 10c of the box 10 and projecting generally horizontally or at some preselected angled position (not shown) beyond the side portions 10b of the box 10. The stop rods 52 are utilized to limit the relative movement between the back portion 10c of the box 10 and tines 28 of the truck 26 as shown in FIGS. 4,5.

It will be noted from a consideration of FIGS. 1A,2,4-6, that the pivot point 22 of the box 10 is desirably disposed rearwardly of the center of gravity G—G a distance D (FIGS. 2,4-6) to accelerate and facilitate the dumping operation illustrated in such figures.

ALTERNATIVE EMBODIMENTS

It will be understood by those skilled in the art that alternatively, as shown in FIG. 2, the second stop rods 52² or 52⁹ (FIG. 9) project from either the bottom portion 10a or the side portions 10b of the box 10 in the case where the back portion 10c is disposed within the side portions 10b of the box 10 (FIGS. 2,9).

FIG. 7 shows a stirrup member 20⁷ having its pivot rod 22⁷ journaled in brackets 24⁷, which brackets 24⁷ depend from the bottom portion 10a of the box 10⁷. In the embodiment of FIG. 7, the box 10⁷ may be provided with four legs 54. It will be noted in FIG. 7 that the truck (not shown) is provided with a single relatively wide tine 28⁷. Rotary dumping movement may be limited by the forward portions of the bottom portion 10a of the box 10⁷ striking the ground 14.

FIG. 8 shows a generally vertically mounted stirrup member 20⁸ having its tine receiving cavity 20a⁸ disposed in a generally vertical plane substantially parallel to the side portion 10b⁸ of the box 10⁸. In this embodiment the truck (not shown) has a single vertical tine 28⁸ which is received in the tine receiving cavity 20a⁸.

As shown in FIGS. 2 and 9, the forward portions of the bottom portion 10a may be tapered downwardly at 56 to facilitate scoop loading of the dump type box 10 (FIG. 2) or 10⁹ (FIG. 9).

In order to prevent entanglement of the tine 28⁷ (FIG. 7), 28⁸ (FIG. 8) or the tines 28 shown in FIGS. 1A,2-6 between 75 either the front members 16 and the brackets 24 and the back

members 18, a first guard means 58 (shown in the left-hand portions of FIG. 9) and a second guard means 60 (shown in the right-hand portions of FIG. 9) may be employed. In FIG. 9, an arcuate first guard means 58a is shown in solid lines extending between the top of the front member 16 and the top of the bracket 24. Alternatively, a straight line type plate or first guard means 58b may extend from the top of the first member 16 to the top of the first stop rod 50 and from the top of the first stop rod 50 to the top of the bracket 24. In the case where the first stop rod 50 is not employed, a straight plate type first guard means 58c may extend directly (as shown in the lower dotted lines of FIG. 9) from the top of the first member 16 to the top of the bracket 24.

Referring now to the right-hand portions of FIG. 9, an arcuate second guard means 60a is shown by the solid lines and a straight plate type second guard means 60b is shown in the dotted lines. Both second guard plates 60a and 60b extend substantially from the top of the bracket 24 to the top of the back member 18.

SUMMARY OF THE ACHIEVEMENTS OF THE OBJECTS OF THE INVENTION

It will be recognized by those skilled in the art that the objects of this invention have been achieved by providing an improved dump type box 10 (FIGS. 1A,2-6), 10⁷ (FIG. 7), 10⁸ (FIG. 8) and 10⁹ (FIG. 9), for use with a lift fork truck 26 of the type shown in FIG. 1B. This improved apparatus eliminates the use of the conventional latch (not shown) used to dump the bulk material 48, eliminates the use of the conventional attachments on the fork lift truck 26, which attachments (not shown) are operable to dump the box 10 (FIGS. 1A,2-6), 10⁷ (FIG. 7), 10⁸ (FIG. 8) and 10⁹ (FIG. 9); does not require a complicated mechanism (not shown) on the fork lift truck 26 to cause dumping of the bulk material 48 therefrom; eliminates the use of conventional overhead booms (not shown) to cause the dumping of the bulk material 48 from the box 10 (FIGS. 1A,2-6), 10⁷ (FIG. 7), 10⁸ (FIG. 8) and 10⁹ (FIG. 9); is simple and rugged in structure; has few moving parts; requires little or no maintenance; has a long operational life; and is readily adapted to any required volume or capacity of the load carrying cavity 12 (FIG. 1A).

While in accordance with the patent statutes, preferred and alternative embodiments of this invention have been illustrated and described in detail, it is to be particularly understood that the invention is not limited thereto or thereby.

We claim:

1. In combination:

a. a supporting surface; and
b. a material handling apparatus having:

1. a dump type box having a bottom portion, opposed side portions and a back portion defining a load carrying cavity adapted to receive a bulk material;

2. said dump type box also having:

a. a front fork engaging member on one portion of a side portion and said bottom portion,

b. a rear fork engaging member on said one portion and spaced from said front fork engaging member, and

c. a fork engaging stirrup member on said one portion, disposed between said front fork engaging member and said rear fork engaging member and pivotable on said one portion,

3. a lifting fork device reciprocable in a vertical plane with respect to said supporting surface and having a tine,

4. said tine being insertable through said fork engaging stirrup member while said dump type box is in a rest position and into registry with said front fork engaging member and said rear fork engaging member so that said tine engages said front fork engaging member and said rear fork engaging member when said tine moves said dump type box away from said rest position into a box transporting position,

5. said tine then being operable to return said filled dump type box to said rest position to permit said tine to clear said front fork engaging member, while said dump type box is in said rest position,

6. said tine then being operable to move said dump type box away from said rest position so that said filled dump type box rotates about said fork engaging stirrup member into a dumping position, and

7. said front fork engaging member and said rear fork engaging member defining a tine engaging curve registerable with said tine preparatory for the lifting operation.

2. In combination:

a. a supporting surface; and

b. a material handling apparatus having:

1. a dump type box having a bottom portion, opposed side portions and a back portion defining a load carrying cavity adapted to receive a bulk material,

2. said dump type box also having:

a. a front fork engaging member on one portion of a side portion and said bottom portion,

b. a rear fork engaging member on said one portion and spaced from said front fork engaging member, and

c. a fork engaging stirrup member on said one portion, disposed between said front fork engaging member and said rear fork engaging member and pivotable on said one portion,

3. a lifting fork device reciprocable in a vertical plane with respect to said supporting surface and having a tine,

4. said tine being insertable through said fork engaging stirrup member while said dump type box is in a rest position and into registry with said front fork engaging member and said rear fork engaging member so that said tine engages said front fork engaging member and said rear fork engaging member when said tine moves said dump type box away from said rest position into a box transporting position,

5. said tine then being operable to return said filled dump type box to said rest position to permit said tine to clear said front fork engaging member, while said dump type box is in said rest position,

6. said tine then being operable to move said dump type box away from said rest position so that said filled dump type box rotates about said fork engaging stirrup member into a dumping position; and

7. said rear fork engaging member and said fork engaging stirrup member defining a tine engaging curve registerable with said tine preparatory for the dumping operation.

3. In combination:

a. a supporting surface; and

b. a material handling apparatus having:

1. a dump type box having a bottom portion, opposed side portions and a back portion defining a load carrying cavity adapted to receive a bulk material,

2. said dump type box also having:

a. a front fork engaging member on said one portion of a side portion and said bottom portion,

b. a rear fork engaging member on said one portion and spaced from said front fork engaging member, and

c. a fork engaging stirrup member on said one portion, disposed between said front fork engaging member and said rear fork engaging member and pivotable on said one portion,

3. a lifting fork device reciprocable in a vertical plane with respect to said supporting surface and having a tine,

4. said tine being insertable through said fork engaging stirrup member while said dump type box is in a rest position and into registry with said front fork engaging member and said rear fork engaging member so that said tine engages said front fork engaging member and

- said rear fork engaging member when said tine moves said dump type box away from said rest position into a box transporting position,
5. said tine then being operable to return said filled dump type box to said rest position to permit said tine to clear said front fork engaging member, while said dump type box is in said rest position,
6. said tine then being operable to move said dump type box away from said rest position so that said filled dump type box rotates about said fork engaging stirrup member into a dumping position, and
7. having a first guard means on said one portion to prevent entanglement of said tine between said front fork engaging member and said fork engaging stirrup member.
- 15
4. In combination:
- a supporting surface; and
  - a material handling apparatus having:
    1. a dump type box having a bottom portion, opposed side portions and a back portion defining a load carrying cavity adapted to receive a bulk material,
    2. said dump type box also having:
      - a front fork engaging member on one portion of a side portion and said bottom portion,
      - b. a rear fork engaging member on said one portion and spaced from said front fork engaging member, and
      - c. a fork engaging stirrup member on said one portion disposed between said front fork engaging member and said rear fork engaging member and pivotable on said one portion,
    3. a lifting fork device reciprocable in a vertical plane with respect to said supporting surface and having a tine,
    4. said tine being insertable through said fork engaging stirrup member while said dump type box is in a rest position and into registry with said front fork engaging member and said rear fork engaging member so that said tine engages said front fork engaging member and said rear fork engaging member when said tine moves said dump type box away from said rest position into a box transporting position,
    5. said tine then being operable to return said filled dump type box to said rest position to permit said tine to clear said front fork engaging member, while said dump type box is in said rest position,
    6. said tine then being operable to move said dump type box away from said rest position so that said filled dump type box rotates about said fork engaging stirrup member into a dumping position; and
    7. having a second guard means on said one portion to prevent entanglement of said tine between said fork engaging stirrup member and said rear fork engaging member.
- 55
5. In combination:
- a supporting surface; and
  - a material handling apparatus having:
    1. a dump type box having a bottom portion, opposed side portions and a back portion defining a load carrying cavity adapted to receive a bulk material,
    - a. said bottom portion being adapted to rest in a normal rest position on said supporting surface,
    2. said dump type box also having:
      - a. opposed front fork engaging members on said opposed side portions,
      - b. opposed rear fork engaging members on said opposed side portions and spaced from said front fork engaging members, and
      - c. opposed fork engaging stirrup members on said opposed side portions, disposed between said opposed front fork engaging members and said opposed rear fork engaging members and pivotable on said opposed side portions,
    3. a lifting fork device reciprocable in a vertical plane with respect to said supporting surface,
- 60
- 65
- 70
- 75

4. said lifting fork device being insertable through said opposed fork engaging stirrup members while said dump type box is in said rest position and into registry with said opposed front fork engaging members and said opposed rear fork engaging members so that said lifting fork device engages said opposed front fork engaging members and said opposed rear fork engaging members when said fork lifting device moves said dump type box away from said rest position into a box transporting position,
5. said lifting fork device then being operable to return said filled dump type box to said rest position to permit said lifting fork device to clear said opposed front fork engaging members, while said dump type box is in said rest position,
6. said lifting fork device then being operable to move said dump type box away from said rest position so that said filled dump type box rotates about said opposed fork engaging stirrup members into a dumping position,
7. each of said opposed front fork engaging members and said opposed rear fork engaging members defining a fork engaging curve registerably with said fork lifting device preparatory for the lifting operation,
6. In combination:
- a supporting surface; and
  - a material handling apparatus having:
    1. a dump type box having a bottom portion, opposed side portions and a back portion defining a load carrying cavity adapted to receive a bulk material,
    - a. said bottom portion being adapted to rest in a normal rest position on said supporting surface,
    2. said dump type box also having:
      - a. opposed front fork engaging members on said opposed side portions,
      - b. opposed rear fork engaging members on said opposed side portions and spaced from said front fork engaging members, and
      - c. opposed fork engaging stirrup members on said opposed side portions, disposed between said opposed front fork engaging members and said opposed rear fork engaging members and pivotable on said opposed side portions,
    3. a lifting fork device reciprocable in a vertical plane with respect to said supporting surface,
    4. said lifting fork device being insertable through said opposed fork engaging stirrup members while said dump type box is in said rest position and into registry with said opposed front fork engaging members and said opposed rear fork engaging members so that said lifting fork device engages said opposed front fork engaging members and said opposed rear fork engaging members when said fork lifting device moves said dump type box away from said rest position into a box transporting position,
    5. said lifting fork device then being operable to return said filled dump type box to said rest position to permit said lifting fork device to clear said opposed front fork engaging members, while said dump type box is in said rest position,
    6. said lifting fork device then being operable to move said dump type box away from said rest position so that said filled dump type box rotates about said opposed fork engaging stirrup members into a dumping position, and
    7. each of said opposed rear fork engaging members and said fork engaging stirrup members defining a fork engaging curve registerable with said fork lifting device preparatory for the dumping operation.
7. In combination:
- a supporting surface; and
  - a material handling apparatus having:
    1. a dump type box having a bottom portion, opposed side portions and a back portion defining a load carrying cavity adapted to receive a bulk material,

2. said dump type box also having:
  - a. a front fork engaging member on either a side portion or said bottom portion,
  - b. a rear fork engaging member on the same portion as said front fork engaging member and spaced from said front fork engaging member, and
  - c. a fork engaging stirrup member on said same portion, disposed between said front fork engaging member and said rear fork engaging member and pivotable on said same portion,
3. a lifting fork device reciprocable in a vertical plane with respect to said supporting surface and having a tine,
4. said tine being insertable through said fork engaging stirrup member while said dump type box is in a rest position and into registry with said front fork engaging member and said rear fork engaging member so that said tine engages said front fork engaging member and said rear fork engaging member when said tine moves said dump type box away from said rest position into a box transporting position, said tine clearing the inside top surface of said fork engaging stirrup member when said dump type box is in said box transporting position,
5. said tine then being operable to return said filled dump type box to said rest position to permit said tine to clear said front fork engaging member, while said dump type box is in said rest position,
6. said tine then being operable to engage said inside top surface of said fork engaging stirrup member and to move said dump type box away from said rest position so that said filled dump type box rotates about said fork engaging stirrup member into a dumping position.
8. The combination recited in claim 7 wherein said tine is oscillatable between a first position substantially parallel to said supporting surface and a second position disposed at an angle to said supporting surface.
9. The combination recited in claim 7 wherein said dump type box rotates into said dumping position when the forward portion of said dump type box engages said supporting surface.
10. The combination recited in claim 7 wherein said dump type box has a first stop means on one of said opposed side portions for engaging such tine to limit said dumping position of said dump type box.
11. The combination recited in claim 7 wherein said dump type box has a second stop means on one of said back portion, side portion or bottom portion, for limiting the relative movement between said back portion and said fork lifting device.
12. The combination recited in claim 7 wherein fork engaging stirrup member is disposed rearwardly of the center of gravity of said dump type box.
13. The combination recited in claim 7 wherein said same portion is said bottom portion.
14. The combination recited in claim 7 wherein said same portion is one of said side portions.
15. The combination recited in claim 13 wherein said stirrup member is substantially vertical and said tine is substantially vertical.
16. The combination recited in claim 13 wherein said stirrup member is substantially horizontal and said tine is substantially horizontal.
17. The combination recited in claim 14 wherein said one portion is substantially vertical and said tine is substantially vertical.
18. The combination recited in claim 14 wherein said one

portion is substantially horizontal and said tine is substantially horizontal.

19. In combination:

- a. a supporting surface; and
- b. a material handling apparatus having:
  1. a dump type box having a bottom portion, opposed side portions and a back portion defining a load carrying cavity, adapted to receive a bulk material,
  - a. said bottom portion being adapted to rest in a normal rest position on said supporting surface,
  2. said dump type box also having:
    - a. opposed front fork engaging members on said opposed side portions,
    - b. opposed rear fork engaging members on said opposed side portions and spaced from said front fork engaging members, and
    - c. opposed fork engaging stirrup members on said opposed side portions, disposed between said opposed front fork engaging members and said opposed rear fork engaging members and pivotable on said opposed side portions,
  3. a lifting fork device reciprocable in a vertical plane with respect to said supporting surface,
  4. said tine being insertable through said fork engaging stirrup member while said dump type box is in a rest position and into registry with said front fork engaging member and said rear fork engaging member so that said tine engages said front fork engaging member and said rear fork engaging member when said tine moves said dump type box away from said rest position into a box transporting position, said tine clearing the inside top surface of said fork engaging stirrup member when said dump type box is in said box transporting position,
  5. said tine then being operable to return said filled dump type box to said rest position to permit said tine to clear said front fork engaging member while said dump type box is in said rest position,
  6. said tine then being operable to engage said inside top surface of said fork engaging stirrup member and to move said dump type box away from said rest position so that said filled dump type box rotates about said fork engaging stirrup member into a dumping position.
20. The combination recited in claim 19 wherein said lifting fork device is oscillatable between a first position substantially parallel to said supporting surface and a second position disposed at an angle to said supporting surface.
21. The combination recited in claim 19 wherein said dump type box rotates into said dumping position when the forward portion of said bottom portion of said dump type box engages said supporting surface.
22. The combination recited in claim 19 wherein said dump type box has a first stop means on one of said opposed side portions for engaging such fork lifting device to limit said dumping position of said dump type box.
23. The combination recited in claim 19 wherein said dump type box has a second stop means for limiting the relative movement between said back portion and said fork lifting device.
24. The combination recited in claim 19 wherein said opposed fork engaging stirrup members are disposed rearwardly of the center of gravity of said dump type box.
25. The combination recited in claim 7 wherein said bottom portion has a taper of the front thereof to facilitate scoop loading of said dump type box.
